UNITED STATES PATENT OFFICE

2,172,671

REFRIGERATOR OR COOLER

Carl G. Carlson, Chicago, Ill.

Application February 17, 1938, Serial No. 190,901

7 Claims. (Cl. 62—116)

My invention belongs to that general class of devices known as refrigerators or coolers, and is directed more particularly to an improvement in the type of refrigerator generally used in domestic service.

The invention has among its objects the production of a refrigerator in which I utilize what is waste space in certain types of refrigerators now on the market. A certain amount of usable space is wasted because it is not fully utilized in refrigerators with an upper cooling compartment and with a separate lower compartment containing the refrigerating equipment or unit provided for supplying the cooling medium to the cooling coil or unit in the food cooling chamber. There are types of refrigerators in which there is a comparatively large food cooling compartment at the top or upper portion of the refrigerator having its own cooling coil and separate door, and a further uncooled chamber or compartment below the main compartment in which is arranged the unit for supplying the cooling medium to the said evaporator or cooling coil in the compartment above. In most instances the equipment in the lower compartment fills only a small portion at the rear of the compartment and I propose to utilize the excess space in this compartment for auxiliary cooling purposes, the same constituting convenient cooling chambers for articles such as bottled goods, for instance, milk and beverages, or for eggs or butter, etc., which are not exposed when the door to the upper food compartment is opened and which may be readily and conveniently removed without opening the upper door and exposing the contents thereof.

The invention has among its general objects the production of a refrigerator of the kind described which is simple, convenient, efficient, and which may be equipped with my improved auxiliary cooler at a very slight expense.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawing, wherein like reference characters indicate like or corresponding parts:

Fig. 1 is a side elevation of a refrigerator showing certain portions in dotted lines and the side wall of the lower portion broken away to show the interior;

Fig. 2 is substantially an enlarged sectional

view of a portion of the lower compartment illustrated in Fig. 1, corresponding with the lower left hand corner of Fig. 1; and

Fig. 3 is a sectional view taken substantially on line 3—3 of Fig. 2.

Referring to the drawing, in which only one embodiment of my invention is shown, I designates generally a domestic type of refrigerator having an upper chamber or compartment 2 for the storage of food or other commodities, and a door 3 for closing and sealing the compartment. At the lower portion or bottom of the refrigerator is a compartment 4 entirely separate and insulated from the upper compartment above and which may be closed by a door 5 hinged either at the bottom or at the side so it may be opened to display the interior. Any suitable type of evaporator or cooling coil 6 is arranged in the compartment 2, this ordinarily being arranged in the upper portion and the compartment provided with suitable shelves (not shown) for carrying the food products to be chilled or cooled. Within the lower compartment 4 is arranged the refrigerating unit for supplying the cooling medium to the evaporator coil, the unit as a whole being generally designated by the numeral 7, and as shown in the drawing, consisting of the compressor 8, motor 9, condenser 10, receiving tank 11, receiving valve 12, and the necessary piping 13 and 14 connecting the compressor and receiving valve with the evaporator 6 in the upper compartment. Generally speaking, this is a customary refrigerator type, it being immaterial whether the evaporator 6 or cooling coil is provided with cooling fluid from an electric, gas or other circulating unit, nor does it matter what particular type of evaporator coil is used. As a general practice in a domestic refrigerator of this type it is customary to keep milk bottles or beverage bottles on the shelves and not use or cool the lower compartment. Bottles vary in height and size, and sometimes must be laid down flat on a shelf in order to fit in the box. If they are placed at the back on a shelf, it is necessary to remove food in front before removing the bottles or packages, while if they are placed in front, it is necessary to remove them to reach articles in back, and generally speaking, the arrangement is inconvenient, and in lifting milk bottles, for example, back and forth, they are often upset.

I propose to utilize the front portion of the lower compartment 4 which is otherwise waste space as an auxiliary cooling space, and provide a coil extending transversely across the compartment from side to side and forming, as it were,

the partition between the front portion and the rear portion of the compartment at the bottom of the refrigerator. I also provide on the door 5 of the lower compartment a container for milk bottles, beverage bottles, packaged butter, eggs or the like, which are readily accessible and removable by merely opening the door a slight distance without in any way opening or exposing the top compartment, which is the normal food compartment, to warm room air. In the drawing I have illustrated the door 5 hinged or pivotally supported at the bottom, so that it may be tilted outwardly a short distance. It is, of course, immaterial whether the door 5 is hinged at the bottom or the side. Within this lower compartment is arranged an evaporator or cooling coil 19 which is preferably of a flat type and of a length to extend substantially across the compartment from side to side and the desired depth from the top. This coil is shown connected by the piping 20 and 21 to the compressor and receiving tank, respectively, or to the piping 15 and 16, the same constituting an auxiliary or supplemental cooling coil which may be operated from the unit supplying the cooling fluid to the evaporator 6 without, to any appreciable extent, affecting the efficiency of the evaporator 6 or overlapping the unit 1. This coil is shown supported by brackets 22 from the top wall 23 of the lower compartment. I have not considered it necessary to illustrate the coil 19 in detail, since the narrow or fin type of evaporator coil may be employed, suitable means well known in the art being provided for regulating the flow of cooling fluid to or from the coil.

As shown, a wall of insulating material 25 extends adjacent the evaporator coil but slightly spaced therefrom at the rear side thereof and this wall may, if desired, extend down to the bottom. As illustrated, however, it extends part way and only to slightly below the coil, there being a cooperating wall 31 of insulating material mounted on the door. As shown, mounted on the door is a receptacle consisting of a bottom 28 which is insulated, side walls 29 and a rear wall 30 which carries the insulation 31. A basket or wire type container may be employed if desired. When the door 5 is closed the rear wall of the receptacle forms a continuation of the evaporator insulated wall at the rear of the coil. It will be noted by referring to Fig. 2 that when the door 5 is closed, the coil 19 substantially forms a rear wall for the container but is carried by the top 23 of the compartment and stationary rather than movable with the door 5. When the door is closed, chilled air may descend from the coil 19 to the lower part of the receptacle and thence travel upwardly from the bottom of the receptacle to the top, whence it circulates over the coil and again descends to the bottom, etc. chilling or cooling the contents of the receptacle. It is customary to provide a control for the cooling of the upper compartment, as for example, a float (not shown) in the evaporator coil 6 which controls the discharge of liquid back to the receiver tank, as well as thermostatically controlled means that will shut off the power to the unit in the lower compartment when the upper compartment reaches a predetermined low level and start the unit operation when the temperature increases. Generally it is not necessary to provide a control for the auxiliary compartment below, but such may be employed if desired, but rather than controlling operation of the compressor, etc., it is preferred to provide some means

such as the well known float control for regulating the discharge of fluid to and from the evaporator or the well known type of expansion valve arranged in the system.

It is seen that this improvement, including an evaporating coil of compact form in and extending across the lower compartment in proximity to the door, provides an auxiliary cooling space for certain articles without in any way interfering with the installation, operation or control of the refrigerating unit in the rear part of the lower compartment or operation of the evaporator coil 6. The space is so small between the door and the evaporator or cooling coil that the unit ordinarily employed for cooling the upper compartment is sufficient to take on the extra load of cooling the lower space. Brackets or shelf 40 for carrying a pan 41 during defrosting may be provided. The convenience and utility of this improvement is readily obvious. Access may be had to the main compartment or to auxiliary compartment without exposing the other one.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In a refrigerator of the kind described, having a plurality of associated compartments each having a door for access to the compartment, a refrigerating unit including an evaporator coil arranged in each compartment and a compressor, condenser, receiver and associated parts arranged in one of the compartments, the evaporator in said last mentioned compartment extending transversely across the compartment proximate the door thereto but spaced inwardly from the door, partition means separating said last mentioned evaporator from the remainder of the cooling mechanism to form a second cooling compartment, and a receptacle mounted on said door of a size to extend between the door and evaporator but having the inner side wall cut away at the evaporator, whereby the evaporator substantially constitutes a rear wall for the receptacle.

2. The combination in a refrigerator having two associated compartments of a refrigerating unit arranged in one compartment of the refrigerator and including a cooling coil in each compartment, a door for each compartment, the door of the compartment containing said unit provided with an inner wall spaced from the body of the door and constituting a receptacle, the cooling coil in said compartment extending transversely across the compartment proximate the door but spaced back therefrom substantially in the plane of the said spaced inner wall and constituting an extended wall of the receptacle when the door is closed.

3. In a refrigerator of the kind described having a plurality of associated compartments and in combination, a refrigerating unit having a compressor, driving means therefor, receiving tank and condenser arranged in one compartment, and including a cooling coil arranged in each compartment, a door for each compartment, the door of the compartment containing said unit having a receptacle mounted on the inner side, the evaporator coil in said compartment ex-

5 tending transversely across the compartment proximate the door but spaced back therefrom a distance substantially equal to the thickness of the receptacle and mounted with its front face substantially in the plane of the wall of the receptacle, and insulating means interposed between the evaporator coil and receptacle and the refrigerating unit.

10 4. In a refrigerator of the kind described having two associated compartments arranged one above the other and in combination, a refrigerating unit including a cooling coil in each compartment and a compressor, driving means for the compressor, a condenser, receiving tank and associated parts arranged in the lower compartment at the rear thereof, a door for each compartment, the door of the lower compartment having a receptacle mounted at the inner side thereof, the cooling coil in said lower compartment depending from the top wall thereof and extending transversely across the compartment and substantially constituting a side therefor when the door is closed, and insulation interposed between said receptacle and said compressor and associated parts in the compartment.

15 5. A refrigerator of the kind described having upper and lower compartments, a cooling coil arranged in each compartment, a door for each compartment arranged one above the other, a cooling coil in the lower compartment spaced back from the door thereof and extending transversely across the compartment substantially from side to side, and a wall of insulating material positioned in the compartment at the rear of said cooling coil and extending between the top and bottom and side walls of the compartments to provide a cooling chamber, said rear wall having a recessed portion therein, the respective cooling coil being positioned therein with

the outer face of the coil substantially flush with the remainder of the wall.

6. A refrigerator of the kind described having separate upper and lower compartments insulated from each other, a separate cooling coil arranged in each compartment, means for connecting said coils to a common source of cooling fluid, a separate door for each compartment arranged one above the other, the cooling coil in the lower compartment spaced back from the door thereof and extending transversely across the compartment, and a wall of insulating material positioned in the compartment at the rear of said cooling coil and extending between the top and bottom and side walls of the compartments to provide an auxiliary cooling chamber, the lower portion of said wall being removable and the upper portion of said wall having a coil receiving recess therein to position the respective cooling coil substantially in the plane of the removable lower portion, and means on the inner face of the said lower door for carrying articles to be cooled.

10 7. The combination in a refrigerator having two associated but separate independent compartments, of a refrigerating unit arranged in one compartment of the refrigerator and including a cooling coil in each compartment connected to a common source of cooling fluid, an independent door for each compartment, the door of the compartment containing said unit provided with an inner wall spaced back and carried from the body of the door at the inner side thereof and constituting a receptacle, the cooling coil in said last mentioned compartment extending transversely across the compartment proximate the door but spaced back therefrom and lying substantially in the plane of the said spaced receptacle inner wall and constituting an extended wall of the receptacle when the door is closed.
